United States Patent Office

Des. 211,647
Patented July 9, 1968

211,647

KNICK-KNACK SHELF OR SIMILAR ARTICLE

William E. Hardin, Rte. 1, Box 189,
Litchfield, Ohio 44253

Filed May 25, 1967, Ser. No. 7,262

Term of patent 14 years

(Cl. D33—3)

Fig. 1

Fig. 2

Fig. 3

Fig. 4

Fig. 5

 I claim:

The ornamental design for a knick-knack shelf or similar article, as shown.
